TOY BLOWPIPE

Leonhard Höfler, 70 Hardstrasse, Furth,
Bavaria, Germany

Filed Feb. 17, 1964, Ser. No. 78,656

Claims priority, application Germany Aug. 23, 1963

Term of patent 3½ years

(Cl. D34—15)

FIG. 1

FIG. 3

FIG. 2

FIG. 1 is a front elevational view of a toy blowpipe embodying my new design;

FIG. 2 is a perspective view looking upwardly from one side of the toy blowpipe, and

FIG. 3 is a perspective view looking downwardly from one end of the toy blowpipe.

The opposite side of the toy blowpipe of this design is substantially similar to the side illustrated.

I claim:

The ornamental design for a toy blowpipe, as shown and described.
